J. D. GOOD

ADJUSTABLE SHADE ROLLER SUPPORT

Filed Sept. 29, 1924

INVENTOR
John D. Good
BY
Howard C. Thompson
ATTORNEY

UNITED STATES PATENT OFFICE.

JOHN D. GOOD, OF HOBOKEN, NEW JERSEY.

ADJUSTABLE SHADE-ROLLER SUPPORT.

Application filed September 29, 1924. Serial No. 740,475.

To all whom it may concern:

Be it known that I, JOHN D. GOOD, a citizen of the United States, and residing at Hoboken, in the county of Hudson and State of New Jersey, have invented certain new and useful Improvements in Adjustable Shade-Roller Supports, of which the following is a specification, such as will enable those skilled in the art to which it appertains to make and use the same.

This invention relates to shade roller supports and particularly to the provision of means for adjustably supporting the roller longitudinally of the window opening and to support the roller in predetermined positions of adjustment, and the object of the invention is to provide a supporting device of the class specified by means of which the roller of a shade may be moved into several positions from the top of a window frame to a point substantially midway of the window opening whereby the shade may be drawn down to form a closure for the major portion of the window opening and whereby the top window may be drawn down and a room ventilated; a still further object being to provide a device of the class specified whereby when the window is opened from the top and the shade roller moved to a point below the open portion of the window the rattling of the shade is obviated; a further object being to provide means for raising and lowering the shade roller supporting means as well as to provide means for releasing the supporting devices to permit of the movement of the supporting means into different positions; a still further object being to provide means for adjusting the device to windows of different width and to suit rollers of different lengths; and with these and other objects in view the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is an inside view of the top portion of a window diagrammatically illustrating my improved device mounted in connection

therewith and illustrating the method of its use;

Fig. 2 is a partial transverse section through the window frame showing one side of my supporting device;

Fig. 3 is a detail face view of a part of the construction which I employ;

Fig. 4 is a partial section on the line 4—4 of Fig. 2; and,

Fig. 5 is a sectional detail view of one of the rails which I employ.

In Fig. 1 of the drawing I have diagrammatically illustrated my invention mounted in connection with a window construction 10 and in said figure 11 represents the top sash, 12 the bottom sash, and 13 the roller of a shade.

My improved device comprises two guide rails 14 which are of similar construction throughout and on which are slidably mounted frames 15 also of similar construction. The rails 14 are of I-beam formation in cross section as indicated in Fig. 2 of the drawing and are provided with flanged ends 16 and 17, the flange 16 being on the outer face, and said rails are tubular in form as clearly shown in Figs. 2 and 5 of the drawing. The frames 15 consist of substantially L-shaped members 18, the extensions of which are of rod-formation and to the extensions 19 are secured two channeled shoe members 20 which interlock with the flanges 16 of the rails 14 as clearly shown in Figs. 2 and 3 of the drawing, the other extensions 21 are provided in their top faces with longitudinal grooves 22, see Figs. 2 and 4, and are adapted to extend into an intermediate tubular section 23 and to telescope relatively thereto. Mounted on the extension 21 are two slidable blocks 24 which are keyed to the said extensions by keys 25 operating in the grooves 22 and in threaded engagement with said blocks is an adjustment rod 26 having left and right hand threads at its end whereby the blocks may be adjusted into predetermined positions on the members 21 of the frames 15 to suit shade rollers of predetermined length. The usual shade roller supporting brackets 27 are mounted in connection with the blocks 24 as clearly seen in Figs. 2 and 4 of the drawing in which one of the blocks and brackets are shown.

Connected with each of the frames 15 are flexible cords or wires 28 which pass

around pulleys 29 at the top of the window frame and then around a dual pulley construction 30 and are coupled to a single cord or wire 31 at 32, whereby the frames 15 may be moved upwardly and downwardly on the rails 14. By spacing the shoes 20 as illustrated a free sliding action is provided and the frames 15 cannot be jammed, and it will be understood that 10 said frames will drop by gravity but will be raised by a pulley on the cord 31 which will be spaced at one side of the window frame, the illustration in Fig. 1 of the drawing being only diagrammatic.

15 Slidably mounted in the rails 14 are bars 33 having at spaced intervals elongated apertures 34 arranged at an inclination. Coupled with said bars are stop and supporting members 35 having pins 36 operating in the apertures 34 whereby when the bars 33 are in a lowered position the stop members 35 project through the front faces of the rails 14 which serve to limit the downward movement of the frames 15 but 20 by pulling upwardly on said blocks the members 35 are moved inwardly to permit the free sliding of said frame. The upper ends of the bars 33 are coupled together by a cord or wire 37 which passes 25 around two pulleys 38 and a pull string 39 is coupled with the cord or wire 37, whereby a downward pull thereon will move said bars upwardly and the members 35 into an inoperative position. In the diagrammatic illustration of Fig. 1 two of the 30 members 35 are shown, and it will be understood however that any number of these members may be employed in the separate rails.

40 In mounting the rails in connection with the window frame I employ two channel-shaped plates 40 to receive the flanges 11 of the rails 14 and the lower ends of said plates being bent outwardly as shown at 45 41 in Fig. 5 of the drawing to limit the downward movement of the rails 14 and to form a stop for the frame 15 in its lowermost position. The extensions 41 may have spring ends as shown at 42 to 50 engage flanges 43 on the rails to prevent their displacement, while screws 44 are passed through the plates 40 into the window frame in mounting the same in position.

55 It will be understood that in assembling my improved device and in the use thereof, the plates 40 are first secured in proper position to the window frame or the side rails thereof, after which the rails 14 with 60 the bars 33 therein are mounted in position, after which the frame 15, or the members 18 thereof, coupled together through the tube 23 are passed over and slid downwardly on said rails and the blocks 24 are 65 adjusted to support a predetermined shade

roller, or a shade roller suitable for the window in connection with which the device is employed. The pulleys 29, 30 and 38 will be then properly positioned and the cords or wires coupled with the several 70 parts and the device is ready for use. Normally the shade roller 13 will be supported adjacent the upper end of the window frame in the usual manner, the shade may be moved upwardly and downwardly in 75 accordance with the present custom. However, if it is desirable to have the shade drawn fully at the lower end portion of the window opening and yet admit air into a room, the roller 13 may be dropped a 80 predetermined degree and the top sash 11 opened, and the downward adjustment of the shade roller 13 will be to a point substantially mid-way of the window opening. In raising the shade roller from its lowermost position the pull cord 39 is drawn 85 downwardly to move the members 35 inwardly and the cord 31 pulled downwardly to raise the frame 15 and the roller 13 mounted thereon.

90 It will be understood that while I have shown certain details of construction for carrying my invention into effect, that I am not necessarily limited to the structural details herein shown and described, and various changes therein and modifications thereof may be made, within the scope of the appended claims, without departing from the spirit of my invention or sacrificing its advantages.

95 Having fully described my invention, what I claim as new and desire to secure by Letters Patent, is:—

100 1. A device for adjustably supporting shade rollers comprising spaced guide rails, a substantially U-shaped frame, the side members of which are provided with bearings movable longitudinally of said guide rails and the crosshead of which is composed of telescoping parts to compensate said frame for the size of the shade roller, shade roller supporting members adjustable on the crosshead of said frame and keyed against 105 rotation thereon, a rod in threaded engagement with said members and adapted to couple the same together and to adjust said members toward and from each other.

110 2. A device for adjustably supporting shade rollers comprising spaced guide rails, a substantially U-shaped frame, the side members of which are provided with bearings movable longitudinally of said guide rails and the crosshead of which is composed of telescoping parts to compensate said frame for the size of shade roller, shade 115 roller supporting members adjustable on the crosshead of said frame and keyed against rotation thereon, a rod in threaded engagement with said members and adapted to couple the same together and to adjust 120 said members toward and from each other.

said members toward and from each other, and means involving pulleys and a single pull cord for moving said frame and a shade roller mounted thereon longitudinally of said guide rails.

3. A device for adjustably supporting shade rollers comprising spaced guide rails, a substantially U-shaped frame, the side members of which are provided with bearings movable longitudinally of said guide rails and the crosshead of which is composed of telescoping parts to compensate said frame for the size of shade roller, shade roller supporting members adjustable on the 15 crosshead of said frame and keyed against rotation thereon, a rod in threaded engagement with said members and adapted to couple the same together and to adjust said members toward and from each other, 20 means involving pulleys and a single pull cord for moving said frame and a shade roller mounted thereon longitudinally of said guide rails, and stop bolts movably mounted in said rails for supporting said 25 frame in predetermined positions on said rails.

4. A device for adjustably supporting shade rollers comprising spaced guide rails, a substantially U-shaped frame, the side members of which are provided with bearings 30 movable longitudinally of said guide rails and the crosshead of which is composed of telescoping parts to compensate said frame for the size of shade roller, shade roller supporting members adjustable on the 35 crosshead of said frame and keyed against rotation thereon, a rod in threaded engagement with said members and adapted to couple the same together and to adjust said members toward and from each other, means 40 involving pulleys and a single pull cord for moving said frame and a shade roller mounted thereon longitudinally of said guide rails, stop bolts movably mounted in said rails for supporting said frame in predetermined 45 positions on said rails, and

means movably mounted in said rails and manually controlled for moving said bolts into inoperative position.

5. A device for adjustably supporting shade rollers comprising spaced guide rails, a substantially U-shaped frame, the side members of which are provided with bearings movable longitudinally of said guide rails and the crosshead of which is composed of telescoping parts to compensate said 50 frame for the size of shade roller, shade roller supporting members adjustable on the crosshead of said frame and keyed against rotation thereon, a rod in threaded engagement with said members and adapted to couple 55 the same together and to adjust said members toward and from each other, means involving pulleys and a single pull cord for moving said frame and a shade roller mounted thereon longitudinally of said 60 guide rails, stop bolts movably mounted in said rails for supporting said frame in predetermined positions on said rails, means movably mounted in said rails and manually controlled for moving said bolts into 65 inoperative position, said last named means including pulleys, and a pull cord.

6. A device for adjustably supporting shade rollers in connection with window frames, said device comprising two guide 75 rails mounted in connection with the side members of the window frame, a member provided with spaced bearings on the separate rails and mounted to freely slide longitudinally of said rails, means for supporting 80 a shade roller in connection with said member, and means involving stop bolts movably mounted in connection with said rails for supporting said member in predetermined position with reference to the window opening, said last named means being movable into operative and inoperative positions.

In testimony that I claim the foregoing as my invention I have signed my name.

JOHN D. GOOD.
